CARRIAGE SHIFT FOR TYPEWRITERS

Columbus E. Norton, Knoxville, Tenn.

Application May 22, 1939, Serial No. 275,086

6 Claims. (Cl. 197—65)

(Granted under the act of March 3, 1883, as
amended April 30, 1928; 370 O. G. 757)

The invention herein described may be manufactured and used by or for the Government for governmental purposes without the payment to me of any royalty thereon.

This invention relates to an improvement in carriage shifting mechanism for typewriters and the like.

One of the objects of this invention is to provide a mechanism for shifting typewriter carriages by pedomotive operation whereby the operator can readily shift such carriage without moving fingers from the keyboard, thereby reducing the errors incident thereto. Another object of this invention is to provide a mechanism for spacing the platen and shifting the carriage of a typewriter which not only effects saving in time but reduces operator fatigue. A further object of this invention is to provide a carriage shifting mechanism which can be easily attached to a standard typewriting support and which still has no integral connection with the typewriter. Other objects of this invention include the provision of a carriage shifting mechanism for a machine which automatically disengages the carriage shifting lever and accordingly provides ample clearance for utilizing the machine in the conventional manner.

I have discovered a mechanism for effecting the above objects which includes in the combination for a typewriter having a movable carriage and a support for said typewriter a platen spacing and carriage return member on said carriage, an arm having a defined path of travel adapted to engage said spacing and return member which is normally manually operated, a treadle associated with said arm through articulated members for engaging said arm with said spacing and return member and advancing the same, and at least one of said articulated members adapted to automatically disengage said arm from said spacing and return member when said treadle is not operated.

In the accompanying drawing, which forms a part of the specification, and wherein reference symbols refer to like parts wherever they occur,

Fig. 1 is a perspective view of a preferred embodiment of my invention wherein the members directly pertaining to the invention are shown in function and those members appurtenant thereto are shown out of function.

Fig. 2 is an enlarged, fragmentary, elevational view of the immediate carriage shifting mechanism shown in Fig. 1, and

Fig. 3 is an enlarged, sectional view taken on line 3—3 of Fig. 2.

In Fig. 1, Fig. 2 and Fig. 3 a desk 1 supports a standard typewriter 3. Affixed to a side panel of the desk 1 is a treadle support 5 to which a treadle 7 is hingedly connected. The treadle 7 is connected to one end of a lever arm 9 which has a bifurcated fulcrum 11 integral with the treadle support 5. The other end of the lever arm 9 is connected to a member 13 which in turn is connected to an elbow member 15 pivoted to a bracket 17 which is securely fastened to the desk top by a screw 19. The bracket 17 also supports a pair of channels, represented by channel 21, which serve as a guide for a wheel 23 connected to one end of an arm 25, which is normally in a substantially vertical position when not operated by treadle 7. The arm 25 is connected at an intermediate point to the elbow member 15 and has its free end provided with a replaceable cushioned striking member 27, which strikes the platen spacing and carriage return member 29 of the typewriter 3, thereby rotating the platen thereof and returning the carriage thereof, in a manner similar to manual operation of said member. The member 13 is so positioned and adjusted in weight as to cause the arm 25 to return to its normal substantially vertical position when pressure is removed from the treadle 7. Referring specifically to Fig. 2, the normal position of arm 25 is in substantial alignment with the pair of channels, represented by channel 21, thereby giving ample clearance to close the desk 1 or perform necessary functions on the machine. It is essential, in connecting the elbow member 15 to the arm 25, that the distance from A to B, B to C and from B to D be equal in order that the path of travel of striking member 27 is defined in a true, horizontal plane, as represented by the arrows 31.

One example of the operation and use of my apparatus is given for use in combination with a conventional typewriter wherein upon completion of a line of typing the treadle is pressed and the elements coacting therewith cause the striking member to engage the spacing and return member on the carriage of the typewriter and to return said carriage to its initial margin position in a manner identical to that used in the manual operation thereof. Furthermore, upon release of pressure upon the treadle, the striking member is immediately disengaged, making it unnecessary to affix any of the members of the mechanism to a standard typing machine.

Another object of the operation and use of my apparatus resides in tabulating and the like

wherein a certain amount of spacing is paramount. In this type of work a staccato manipulation of the treadle will merely produce spacing on the platen while a gentle but firm pressure on the treadle will return the carriage to the desired tabulating zone. These and other uses will be apparent to the skilled operator.

It is evident that there are numerous factors which influence conditions for the most satisfactory operation of the present invention, the actual limits of which, including the specific placement of the coating members, can only be established by a consideration of each typewriting machine and the like with which it may be suitably combined.

The actuating member susceptible to pedomotive operation may be a treadle or knee piece. This actuating member is connected by articulated elements to an elbow member which is in turn connected to an arm which has one extremity associated with a suitable guide arrangement and the other extremity provided with a replaceable, and if so desired, adjustable cushioned striking member which engages the platen spacing and carriage return member on the typewriter. A plurality of holes or other suitable adjusting arrangement is provided in the zone of the connection of the elbow to the arm when the mechanism is equipped to accommodate various typewriters and the like which may have various elevations for the spacing arm and thereby necessitate a considerable adjustment of the adjustable striking member.

In order that the path of travel of the striking member be defined in a true horizontal plane the following distances must be equal at all times: the distance from one extremity of the arm to the elbow connection, the distance from the other extremity of the arm, including the adjustable striking member, to the elbow connection, and the distance from the elbow connection at the arm to the pivotal connection of the elbow to the bracket. Slight deviation from the above distance provisions is permissible only to the extent whereby the striking arm shall remain in contact with the platen spacing and carriage return lever at all times during its path of travel.

Furthermore, in order to insure immediate return of the elbow member and the associated striking arm to its normal position, it is essential that a member or members of the articulated system be so weighted or that resilient means be so employed to insure said immediate return when the platen spacing and/or carriage shifting operation has been completed.

It will be seen, therefore, that this invention actually may be carried out by the use of various modifications and changes without departing from its spirit and scope, with only such changes therein as are imposed by the prior art.

I claim:

1. In combination with a typewriter having a movable carriage and a platen spacing and car-

riage return member on said carriage, an advancing member having an engaging portion movable in a horizontal path of travel and adapted to engage said spacing and return member, pedomotive means for operating said advancing member, and means adapted to maintain said advancing member out of engagement with said spacing and return member when said advancing member is not operated by said pedomotive means.

2. In combination with a typewriter having a movable carriage and a platen spacing and carriage return member on said carriage, an advancing member having an engaging portion movable in a horizontal path of travel and adapted to engage said spacing and return member, pedomotive means for advancing said advancing member, and means adapted to return said advancing member so advanced to its original position.

3. In combination with a typewriter having a movable carriage, an advancing member having an engaging portion movable in a horizontal path of travel and adapted to engage said movable carriage, a member operable to engage and to advance said advancing member with said carriage, and means associated with said advancing member to automatically return said member to its normal disengaged position after said carriage has been fully advanced.

4. In combination with a typewriter having a movable carriage, an advancing member having an engaging portion movable in a horizontal path of travel and adapted to engage said movable carriage, articulated lever elements for engaging and advancing said advancing member, and means associated with said advancing member to automatically return said member to its normal disengaged position after said carriage has been fully advanced.

5. In combination with a typewriter having a movable carriage and a platen spacing and carriage return member on said carriage, an arm having an engaging portion movable in a horizontal path of travel and adapted to engage said spacing and return member which is normally manually operated, and a treadle associated with said arm for engaging said arm with said spacing and return member and advancing the same.

6. In combination with a typewriter having a movable carriage and a platen spacing and carriage return member on said carriage, an arm having an engaging portion movable in a horizontal path of travel and adapted to engage said spacing and return member which is normally manually operated, a treadle associated with said arm through articulated members for engaging said arm with said spacing and return member and advancing the same, and at least one of said articulated members adapted to automatically disengage said arm from said spacing and return member when said treadle is not operated.

COLUMBUS E. NORTON.
